UNITED STATES PATENT OFFICE

2,449,758

BED EQUIPMENT

Elsa Helena Clementine Wikmark,
Stockholm, SwedenApplication August 14, 1944, Serial No. 549,436
In Sweden February 5, 1942

4 Claims. (Cl. 5—334)

1

The present invention relates to bed equipment for avoiding daily bed-making, the said bed equipment comprising a rectangular casing consisting of a top portion and a bottom portion detachable from one another, the bottom portion being longer than the top portion at the head end, the said portions being connected to one another by means of a zipper fastener on each of the longitudinal sides of the casing, and the top portion being provided with protection strips of the blanketlike cloth.

The invention is characterized by the fact that a top quilt and a bottom quilt, which latter is provided with some stiffening cloth in order to hold the bottom sheet stretched or may consist of a thin mattress or pad, are fixed to the casing by means of a rectangular seam or the like at some distance from the edges of the casing so that those parts of the quilts or mattress which lie outside the seams as well as the opposite parts of the casing form free broad border portions between which the sheet portions projecting outside the quilt or mattress are adapted to be inserted.

The top and bottom sheets are fixed to the top quilt and the bottom quilt or thin mattress by means of pockets on the sheets, the said pockets being formed by folding the sides and the ends of the sheets and sewing them together at the corners so that a pocket extending all around each sheet is formed. The free broad border portions of the top quilt and the bottom quilt or thin mattress are inserted in the said pockets. But the sheets can of course be fixed also by buttonholes made therein and by corresponding buttons on the top quilt and the bottom quilt or thin mattress.

An embodiment of the invention is illustrated on the accompanying drawing, in which—

Fig. 1 shows a couch in side elevation.

Fig. 2 is a plan view of a quilt or thin mattress with appertaining sheet, the rectangular seam by which the top quilt or the bottom quilt or thin mattress is fixed to the casing being indicated in dashed lines, the casing being removed for the sake of simplicity.

Fig. 3 is a cross section of the bed and of a casing surrounding the same on the line III—III of Fig. 1.

Fig. 4 shows another method of fixing the top and bottom sheets to the top and bottom quilts.

Fig. 5 is a perspective view showing the means for securing the pillow to the bottom quilt or thin mattress.

In the drawing 1 is the body of the couch; 55

2

2 is a drawer located therein for bed-clothes, 3 is the mattress, and 4 is a support for cushions placed on the couch.

The bed-clothes, such as bottom quilt or thin mattress 6, top and bottom sheets 9 and 8 respectively, pillow 10 with pillow-case, top quilt 7 and/or blanket are adapted to be contained in a casing in the shape of a sleeve 5 which is open at both ends. The bottom portion of the said sleeve is elongated at the head end and the top portion at the foot end. The foot end is normally closed. Along its longitudinal edges the casing is divided into a top portion and a bottom portion and each edge is provided with a zipper fastener 12 with a sliding piece 12a. The bed having once been made, the casing having been closed by means of the zipper fasteners, and the elongated portion of the bottom casing at the head end having been folded over, the bed is laid down in complete condition in the drawer 2, and is taken out therefrom in the same condition and placed on the mattress 3 on the bed support 4.

The elongated portion 13 of the top of the casing which covers the opening at the foot end is folded together with the top quilt, and is fixed to the bottom of the casing by means of a number of straps or button-holes which are buttoned on to corresponding buttons 14. The elongated head portion 20 of the bottom of the casing is folded around the couch cushion 5a and under the end of the mattress 3. The zipper fasteners can be disengaged whereby the top and bottom portions of the casing are separated, which is advantageous when the bed is to be cleaned.

In order to make the bed firm the bottom quilt or thin mattress 6 and the top quilt 7 are fixed by means of a rectangular seam 15 or the like to the bottom and top portions of the casing in such a way that the outer edges are free and that the bottom sheet 8 and the top sheet 9 can be folded over the longitudinal and transverse border portions of the bottom quilt and of the top quilt. The longitudinal and transverse border portions of the bottom sheet 8 are turned in and sewn together by seams 16 in such a way that they form pockets at the back of the sheet, in which pockets the bottom quilt or a thin mattress is to be inserted. In order to further hold the sheets outstretched, if necessary, the quilts can be provided with one or two buttons 16a and the sheets with corresponding button-holes 16b. The top sheet 9 is fixed to the top quilt in the same way as the bottom sheet to the bottom quilt. Instead of the seams 16 and the buttons 16a, the top and

bottom sheets can be fixed to the top and bottom quilts by the folded longitudinal and transverse border portions of the sheets being provided with button-holes 16c adapted to be buttoned on to buttons 16d on the top and bottom quilts. By placing the buttons at a suitable distance from one another the sheets will fit tight to the quilts. On the lower side of the bottom quilt there may be provided also, at the head end, two buttons 18a which engage the button holes 18b of the cover flap 17 of the pillow-case of the pillow 10 so that the pillow is fixed to the bottom quilt or thin mattress, and is held in correct position, which of course is an advantage when the bed equipment is to be moved to and from the bed support. In this case the bottom sheet should be provided with button-holes 21 at this place. The bottom quilt 6 is longer than the top quilt 7 and extends beyond the head end thereof and rests on the cushion 5a which in turn rests on the support 4.

In order to avoid contact with the zipper fasteners 12 and the underlying mattress 3 protection strips 11 of suitable material, teddybear cloth for example, are sewn at 19 onto the top portion of the casing 5 inside the zipper fasteners. The upper quilt is broader than the bottom quilt and the top portion of the casing. When the zipper fastener is locked, the longitudinal edges of the top quilt meet those of the bottom quilt.

The details of the device can of course be varied in many ways without going beyond the scope of the invention.

Having now described my invention, what I claim as new and desire to secure by Letters Patent is:

1. Bed equipment comprising a casing consisting of a top portion and a bottom portion, each having two opposite parallel edges, means detachably securing each of the two parallel edges of the top portion to a corresponding parallel edge of the bottom portion, a top quilt and a bottom quilt, each having opposite parallel edges arranged parallel to said parallel edges of the top and bottom portions of the casing, each quilt being attached to a corresponding portion of the casing along lines parallel to but located at a distance from said parallel edges, and top and bottom sheets each having opposite parallel edges arranged parallel to the parallel edges of the quilts, each of said sheets covering the inner surface of the corresponding quilt and each being of greater width between its parallel edges than the dimension between the parallel edges of the

corresponding quilt, the edge portion of each sheet adjacent each of said parallel edges thereof being folded between the edge portion of the corresponding quilt adjacent said parallel edge thereof and the corresponding casing portion.

2. Bed equipment as defined in claim 1 in which the means for detachably securing the edges of the top and bottom portions of the casing are zipper fasteners and in which the zipper fasteners are covered on the inside of the casing by cloth flaps secured to the casing along lines adjacent to but located at a distance from the parallel edges thereof.

3. Bed equipment as defined in claim 1 in which the edge portions of each sheet adjacent the parallel edges thereof are detachably secured to the corresponding quilt.

4. Bed equipment as defined in claim 1 in which the sheets and quilts are rectangular, the sheets are both longer and wider than the quilts, all four edge portions of each sheet are folded between the corresponding edge portions of the quilts and the corresponding portions of the casing and the corners of the sheets are overlapped and secured together.

ELSA HELENA CLEMENTINE WIKMARK.
